UNITED STATES PATENT OFFICE.

GEORGE E. FELL, OF TRENTON, NEW JERSEY.

REFRIGERATOR.

SPECIFICATION forming part of Letters Patent No. 364,809, dated June 14, 1887.

Application filed January 22, 1887. Serial No. 225,105. (No model.)

To all whom it may concern:

Be it known that I, GEORGE E. FELL, of Trenton, in the county of Mercer and State of New Jersey, have invented a new and Improved Refrigerator, of which the following is a full, clear, and exact description.

This invention relates to a novel form of refrigerating apparatus wherein a central storage-chamber is so arranged in connection with the walls of an outer inclosing-case that, a proper water connection having been established, a constant flow or current of water will be maintained about the said storage-chamber, as will be hereinafter more fully described, and specifically pointed out in the claim.

Reference is to be had to the accompanying drawings, forming a part of this specification, in which similar figures and letters of reference indicate corresponding parts in all the views.

Figure 1 is a sectional elevation of my improved form of refrigerator, the view being taken on line *xx* of Fig. 3, and the apparatus being represented as provided with three storage-chambers, all of which are arranged within an outer inclosing-case. Fig. 2 is a cross-sectional elevation taken on line *yy* of Fig. 1, and Fig. 3 is a sectional plan view taken on line *zz* of Fig. 2.

In constructing such a refrigerator as the one illustrated in the drawings above referred to, I provide an outer shell or case, 10, within which there is arranged an inner case, the interior of which constitutes a storage-chamber; or this case could be divided into two, three, four, or more separate and independent storage-chambers, three of such storage-chambers being represented in the drawings. This inner case is shown at 11, and the two cases, 10 and 11, are separated by a water-space which entirely surrounds the inner case, the two cases being separated and held in the required relative position by any proper form of spacing and holding devices. Communication with the space 12, which surrounds the inner case and separates said case from the outer case, is established by means of an induction-pipe, 13, and an eduction-pipe, 14, the arrangement being such that a connection may

be established with the water-supply pipe of the house or apartment in connection with which the refrigerator is arranged, in which case the water-space of the refrigerator would constitute a portion of said supply-pipe, all 55 water drawn for the use of the house entering the space 12 through the tube 13 and passing from said space through the pipe or tube 14.

In building a refrigerator in accordance with the terms of my invention it is extremely desirable that the water should be forced to flow backward and forward between the several compartments of the case 11; and to that end I arrange a vertical partition, 15, in the space 12, between the tubes 13 and 14, and between the 60 storage-chambers I arrange water-spaces 16 and 17, the rear portion of the upper wall of the water-chamber 16, upon that side of the refrigerator in connection with which the tube 13 is arranged, being extended across the space 65 12, while the forward portion of the lower wall of the water-chamber 16, upon the same side, is carried across said water-space 12, as shown at *k*, other similar partitions being arranged, as shown at *l*, *m*, and *n*, so that water entering the 70 tube 13 will pass forward in the direction of the arrows shown in Figs. 1 and 2 to apertures *a*, formed in the walls of the case 11, above the partition *k*, thence passing through the water-chamber 16, which is centrally divided by a 75 vertical partition, 18, out through other apertures, *b*, formed at the opposite side of the case 11, and into the right-hand side of the water-space beneath the partition *n*, thence downward to apertures *c*, above the partition *m*, 80 through the forward portion of the water-chamber 17, said chamber being divided by a vertical partition, 19, through apertures *d* to the left-hand side of the forward portion of the water-space 12, below the partition *l*, then beneath the lower storage-compartment, then 85 into the right-hand side of the lower portion of the water-space 12, across the right-hand side of the lower storage-compartment to apertures corresponding with the apertures *e* of 90 the space 17, then through the rear portion of said water space or chamber 17 to the left-hand side of the space 12, above the partition *l*, upward and through apertures *f*, leading to the 95 rear portion of the space 16, below the parti- 100

tion *k*, thence through said space and into the right-hand portion of the space 12, above the partition *n*, and finally out through the tube 14, from which arrangement it will be seen that a constant backward and forward flow of water is maintained within the refrigerator, all portions of the storage-chambers of which may be kept at an even low temperature.

Communication with the storage-chambers or compartments of the refrigerator is established by means of an opening in the forward sides of the cases 10 and 11, which opening is arranged to be closed by a door, 20. Under ordinary circumstances the constant flow of fresh, cool water would serve to hold the temperature of the storage-chambers as low as would probably be desired; but in extremely hot weather an ice-storage receptacle might be placed on top of the refrigerator apparatus above described, the said ice-receptacle being arranged so that the water entering the tube 13 would be cooled thereby.

If desired, the cool water passing through the water-space 12 might be drawn off in such quantities as might be desired by means of a stop-cock located at any convenient position— as, for instance, at 21—as shown in Fig. 3.

Having thus fully described my invention, I claim as new and desire to secure by Letters Patent—

A refrigerator consisting of the outer casing, 10, provided with the inlet and outlet openings 13 and 14, the inner casing, 11, having the apertures *a*, *b*, *c*, *d*, *e*, and *f*, and arranged within the outer casing to form a water-space, 12, and divided into storage-chambers, the water-spaces 16 and 17 between the chambers, and divided by vertical partitions 18 and 19, respectively, the partition 15 in the space 12 between the inlet and outlet openings, 40 and the partitions *k*, *l*, *m*, and *n* in the space 12, the partitions *k* *m* being extensions of the lower walls of the spaces 16 and 17, respectively, on opposite sides, and the partition *l* *n* being extensions of the upper walls of the said spaces on opposite sides, substantially as herein shown and described.
